STAPLE SETTING DIE

Otto J. Huelster, Waterbury, Conn., assignor to
 Scovill Manufacturing Company, Waterbury,
 Conn., a corporation of Connecticut

Application January 7, 1946, Serial No. 639,498

11 Claims. (Cl. 218—5)

1

This invention relates to the setting or riveting of staples. More particularly, the invention deals with a die construction employing a rotatable anvil or head adapted to freely rotate in the operation of setting or riveting the prongs of a staple in the operation of securing fastener devices to supports, thereby eliminating the necessity of alinement of the punch die with the staple prongs in performing the setting or riveting operation.

The novel features of the invention will be best understood from the following description, when taken together with the accompanying drawing, in which the separate parts are designated by suitable reference characters in each of the views and, in which:

Fig. 1 is an enlarged sectional view showing upper and lower dies of a tool unit for accomplishing the desired result with said dies in spaced relation and with a staple and button disposed between said dies, and part of the construction being shown in elevation.

Fig. 2 is a view similar to Fig. 1 showing the operation of the tools in attaching the staple and button to a support.

Fig. 3 is a sectional detail view of the lower portion of the anvil at right angles to the position shown in Fig. 1, the section being on the line 3—3 of Fig. 4.

Fig. 4 is a bottom plan view of the anvil, as seen in Fig. 3.

Fig. 5 is a partial section on the line 5—5 of Fig. 4; and

Fig. 6 is a view similar to Fig. 2 showing a modified form of upper die and different type of fastener device.

In Fig. 1, I have shown at 10 the plunger of a press, in which a die holder 11 is detachably mounted through the medium of a set screw 12 in accordance with conventional practice, the screw 12 entering a tapered key slot 13 in the shank 14 of the holder to retain the holder against rotation and axial displacement. The holder 11 has an enlarged collar portion 15, below which is a reduced sleeve 16.

Upon the reduced sleeve 16 is driven or otherwise secured a cup-shaped housing 17, having a large diameter bore 18 fitting the sleeve 16 and a small diameter bore 19, in which is freely, but snugly, mounted an anvil 20. The anvil 20 has a collar portion 21 fitting in the bore 18 and adapted to normally seat upon the shoulder 22. Above the collar 21 is a reduced shank 23 which fits snugly, but freely, in the bore 24 of the sleeve 16. Between the lower end of the sleeve 16 and

5 the collar 21 is an annular member 25, in which are freely arranged a series of bearing balls 26, that is to say, that the diameter of the balls is less than the distance between the lower end of the sleeve 16 and the collar 21 to form a clearance, as at 27, when the anvil is in the normal position, as shown in Fig. 1 of the drawing. In other words, when the anvil is actuated to turn or rivet over the prongs 28 of a staple 29, as seen in Fig. 2, the collar 21 is freely rotatable on the balls 26 to allow the anvil to turn, as later described. The clearance then shifts to a position below the collar 21, as seen at 27' in Fig. 2 of the drawing. By providing the clearance, as at 27', the surface of the collar or flange 21 is maintained out of frictional engagement with the shoulder 22, thus allowing the anvil to rotate freely upon the balls.

10 The lower surface of the anvil 20 has a half-round or cup-shaped recess 30 divided centrally by a blade, rib or partition 31, having a lower bevelled knife edge 32, the curvature of which is eccentric to the curvature of the recess 30, so as to provide a greater depth of the blade 31 15 centrally thereof than at the opposed ends of the blade, as will clearly appear from a consideration of Fig. 3 of the drawing.

15 By providing the greater depth to the blade 31 centrally thereof, the prongs are at all times maintained in their respective halves of the recess 30 to insure proper bending or heading of the prongs. In other words this deep rib maintains the staple legs divided at all times.

20 In Fig. 1 of the drawing is shown at 33 the lower die, which is suitably supported on the table or bed plate of the machine. The die 33 has a recess 34 for supporting the staple 29, with the prongs 28 of the staple directed upwardly, as shown in Fig. 1.

25 In Figs. 1 and 2 of the drawing, I have shown at 35 an open top button for attachment to the staple 29. This button has an annular inward depression 36 in the bottom wall thereof forming an annular groove 37, into which the prongs 28 are adapted to pass. The open end of the button has a radially extending annular enlargement 38 with an inturned edge 39.

30 In Fig. 2 of the drawing, I have shown at 40 a fabric or other support, to which the button 35 is attached by the staple, the attachment to the support having been made, as illustrated in Fig. 2.

35 In the operation of attachment, the fabric 40 is suitably positioned between the staple 29 and button 35 and the punch is lowered, in which op-

eration the anvil 20 passes into the socket 41 of the button and the button is forced down onto the prongs 28 by the plunger actuated anvil 20, the prongs piercing the annular depressed portion 36 of the button in this operation and then entering the recess or socket 30 of the anvil. If the prongs 28 should be in alinement with the rib 31, the sharp knife edge of the rib will then divide the prongs, causing one to move into one side of the anvil socket 30 and the other into the other side and these prongs will, then, be turned or riveted over, as seen at 42, in Fig. 2 of the drawing. When the anvil 20 reaches its lowermost position, as shown in Fig. 2, the annular and slightly rounded peripheral end 43 thereof will extend into a recess 44 in the socket of the button around the indenture 36. The anvil 20 fits freely in the button 35 which allows free separation after the attaching operation has been performed, as seen in Fig. 2 of the drawing.

In stapling operations, as conventionally performed, it has been necessary to line-up or orient staple prongs with an anvil or other forming tool to insure proper operation and to prevent jamming of the prongs. With my construction, the prongs are sub-divided by the rib and it is immaterial what position the staple assumes on the lower die in performing the desired operation.

In Fig. 6 of the drawing, I have shown a slight modification, wherein a die holder 15, similar to the die holder 15 of Fig. 1, is employed and this holder is arranged in an upper die 17, differing from the die 17 in the provision of an annular recess 45 in the lower surface thereof and around the mandrel 20, this recess being provided to receive the upwardly extending wall portions 46 of a stud member 47. The anvil 20 is of the same structure as the anvil 20 of Fig. 1 and, therefore, no further detail description thereof will be given. At 33 is shown the lower die, in which a staple 29, similar to the staple 29 of Fig. 1, is adapted to seat; 40 represents the fabric or other support to which the stud 47 is attached, in crimping-over the staple prongs, as is shown at 42. It will be apparent that by changing the structure of the dies, and, particularly, the upper die, staples may be secured to different types of fastener devices in mounting the same on supports and, in all instances, a sub-divided or partitioned anvil will be employed for maintaining the prongs of the staple in spaced relationship to each other, or sub-divided in the crimping or turning-over operation.

It will be apparent from the foregoing that, in the operation of turning the prong ends, the anvil is free to rotate on its ball bearing support in positioning the partition rib of the anvil socket between the prongs and, further, in guiding the prongs in their curved turned position, as clearly illustrated in Figs. 2 and 6 of the drawing. The thrust is taken up directly upon the bearing balls which provides this free rotary action and the anvil is otherwise free to turn in the upper die, as well as in, or on, the fastener device, which is being secured to a support by a staple.

In considering the die structure, it may be said that this die structure comprises a forming tool, in which the mandrel or forming tool proper has a mounting in the die for movement axially thereof in the inward movement of the forming tool against means forming an anti-frictional thrust bearing, which provides for the free rotation of the tool in the die holder which, in the present construction, comprises the parts 11 and 17.

Having fully described my invention, what I claim as new and desire to secure by Letters Patent is:

1. A tool for stapling fastener devices to supports, a staple setting die comprising a holder, an anvil, means on the anvil and holder providing free rotation of the anvil about its axis in said holder, said anvil having at its lower end a prong-turning socket, said socket having a spherical surface, a rib dividing said socket centrally, and said rib being adapted to space prongs of a staple in the socket at opposite sides thereof in the operation of setting said prongs.

15 2. A tool for stapling fastener devices to supports, a staple setting die comprising a holder, an anvil, means on the anvil and holder providing free rotation of the anvil about its axis in said holder, said anvil having at its lower end a prong-turning socket, said socket having a spherical surface, a rib dividing said socket centrally, said rib being adapted to space prongs of a staple in the socket at opposite sides thereof in the operation of setting said prongs, and said rib having a lower knife edge.

20 3. A tool for stapling fastener devices to supports, a staple setting die comprising a holder, an anvil, means on the anvil and holder providing free rotation of the anvil about its axis in said holder, said anvil having at its lower end a prong-turning socket, said socket having a spherical surface, a rib dividing said socket centrally, said rib being adapted to space prongs of a staple in the socket at opposite sides thereof in the operation of setting said prongs, said rib having 35 a lower knife edge, and said rib being of less depth than the socket and of greater depth centrally of the socket than at side portions of the socket.

4. A tool for stapling fastener devices to supports, a staple setting die comprising a holder, an anvil, means on the anvil and holder providing free rotation of the anvil about its axis in said holder, said anvil having at its lower end a prong turning socket, said socket having a spherical surface, a rib dividing said socket centrally, said rib being adapted to space prongs of a staple in the socket at opposite sides thereof in the operation of setting said prongs, said rib having a lower knife edge, said rib being of less depth than the socket and of greater depth centrally of the socket than at side portions of the socket, and the end of the anvil bordering the socket being rounded.

5. A die structure of the class described comprising a die holder, an anvil mounted in said holder, said anvil and holder having means providing free axial rotation and axial movement of the anvil in the holder, said means including a thrust bearing in said holder for taking upward thrust of said anvil in movement axially of the holder, said anvil having at its lower face a central partitioned socket, and the partition of said socket having a knife edge.

6. In tools for setting the prongs of a staple 65 in attaching the same to a support, a setting tool, said tool having a partitioned prong turning socket in the surface thereof, and means for supporting said tool for free axial rotation in turning and setting prongs of a staple engaged by said tool.

7. In tools of the class described, an anvil comprising cylindrical end portions divided by an enlarged collar portion, a holder having means guiding the cylindrical portions of the anvil for movement axially of said holder, means forming an

anti-frictional thrust bearing in the holder above said collar to take up the thrust of the anvil in movement axially of said holder, and the lower end portion of said anvil having a partitioned staple setting socket.

8. In tools of the class described, an anvil comprising cylindrical end portions divided by an enlarged collar portion, a holder having means guiding the cylindrical portions of the anvil for movement axially of said holder, means forming an anti-frictional thrust bearing in the holder above said collar to take up the thrust of the anvil in movement axially of said holder, the lower end portion of said anvil having a partitioned staple setting socket, and the partition of said socket being of less depth than the socket and of greater depth centrally of the socket than at the periphery of the socket.

9. In tools of the class described, an anvil comprising cylindrical end portions divided by an enlarged collar portion, a holder having means guiding the cylindrical portions of the anvil for movement axially of said holder, means forming an anti-frictional thrust bearing in the holder above said collar to take up the thrust of the anvil in movement axially of said holder, the lower end portion of said anvil having a partitioned staple setting socket, and the holder around said anvil having a recess for reception of a device to which a staple is adapted to be secured.

10. In tools of the class described, an anvil mounted for rotation about its axis, the end of said anvil having a substantially semi-spherical socket divided by a central partition wall, said partition wall terminating its lower end in a relatively sharp bevelled edge formed on an arc of a radius greater than the radius of said socket, and said anvil serving to upset attaching staple members unselectively fed to or set into the tool.

11. In tools of the class described, an anvil mounted for rotation about its axis, the end of said anvil having a substantially semi-spherical socket divided by a central partition wall, said partition wall having its lower end oppositely bevelled into a relatively sharp knife edge, and being formed on an arc of a radius greater than the radius of said socket, and said anvil serving to upset attaching stapling members unselectively fed to or set into the tool.
